Primary Examiner — Kevin K Rudzinski*Assistant Examiner* — Evans David Delesline(74) *Attorney, Agent, or Firm* — Fitzpatrick PC(57) **CLAIM**

I claim the ornamental design for a jewelry band, as shown and described.

DESCRIPTION

FIG. 1 is a top perspective view of a jewelry band showing my new design;

FIG. 2 is a bottom perspective view thereof;

FIG. 3 is a front view thereof;

FIG. 4 is a back view thereof;

FIG. 5 a side view thereof;

FIG. 6 is an opposite side view thereof;

FIG. 7 is a top view thereof; and,

FIG. 8 is a bottom view thereof.

The broken lines shown in the drawings illustrate portions of the jewelry band and form no part of the claimed design.
